UNITED STATES PATENT OFFICE.

WALLACE E. HUGHES, OF PHILADELPHIA, PENNSYLVANIA.

METHOD OF MAKING TUBES.

1,223,282.

Specification of Letters Patent. Patented Apr. 17, 1917.

Application filed September 14, 1915. Serial No. 50,637.

To all whom it may concern:

Be it known that I, WALLACE E. HUGHES, a citizen of the United States, residing in Philadelphia, Pennsylvania, have invented 5 certain Improvements in the Method of Making Tubes, of which the following is a specification.

My invention relates to certain improvements in the process of manufacturing tubes 10 of iron, steel, brass, copper, or other metal, and in the mechanism for carrying out said process.

One object of the invention is to improve the process of making seamless metallic 15 tubes.

A further object of the invention is to roll the tube flush on a mandrel as a core in a single heat.

A still further object of the invention is 20 to use a mandrel of a uniform diameter throughout, which is the form on which the tube is produced.

A further object is to produce tubes of a uniform diameter or tapered as desired.

25 Referring to the drawings, which are in diagram:

Figure 1, illustrates a mandrel on which is located the usual hollow ingot;

Fig. 2, is a view showing the tube in section after being rolled and prior to its withdrawal from the mandrel;

Fig. 3, is a view showing the first step in the method of removing the tube from the mandrel;

35 Fig. 4, is a view, similar to Fig. 3, showing the enlargement, or buckle, carried around the tube; and

Fig. 5, is an exaggerated view, showing the tube clear of the mandrel so that the 40 mandrel can be removed from the tube.

Referring to the drawings, 1 is a mandrel of a uniform diameter throughout and the size of the interior of the tube to be formed. The mandrel may be of any length desired.

45 2 is the hollow ingot from which the tube is made. This hollow ingot is fitted on one end of the mandrel, as in Fig. 1, after being heated to the degree required and is passed between the rolls 3, 3 with the mandrel. 50 These rolls may be the rolls of a 3-high stand or a 2-high stand, or may be the first rolls of a continuous mill, according to the particular mill in which my process is carried out.

55 The ingot is reduced to the proper diameter and gage flush with the mandrel and of

the length required during the rolling operation. After the tube is rolled to the desired diameter it is acted upon to loosen the mandrel, to allow it to be withdrawn from 60 the formed tube.

One method which may be used to withdraw the tube from the mandrel is to hammer or tap the tube longitudinally at *x*, or longitudinally and circumferentially, with 65 sufficient force to produce an enlargement or buckle 4 in the tube at one side, as shown in the drawings. This causes the tube to draw away from the mandrel at this point. Then, by rolling the tube laterally, the 70 buckle is carried around it, which causes the tube to be slightly enlarged so that the mandrel can be withdrawn. This enlargement is almost imperceptible, yet is sufficient to 75 free the mandrel.

The lateral rolling may be accomplished between two surfaces under pressure so as to carry the buckle entirely around the mandrel, as in Figs. 3 and 4 either in a straight 80 line or spiral.

Recesses or slight projections may be formed on the surfaces which are arranged at an incline with respect to the longitudinal line of the tube, so as to cause the tube to travel longitudinally in order to progressively press the tube to release it from the mandrel.

The above description refers to a cylindrical tube, but my invention may be carried out in making tubes oval, square, or other 90 shapes in cross section, using a particularly shaped mandrel in the first step of the process and using a hammer with the mandrel as an anvil to slightly enlarge the tube during 95 the second step of the process.

By using a tapered mandrel and so designing the passes of the rolls, the tube may be rolled tapered on the inside and outside, or either on the inside or outside, as desired, and the outer contour of the tube at one end 100 may be oval in cross section tapering to a round at the opposite end; the tube tapered on the outside is limited in length by the circumference of the rolls.

By the use of my improved process, tubes 105 may be made of greater lengths and of a more uniform gage than heretofore and at a lower cost of manufacture, and limited as to length only by the thickness of the metal of the hollow ingot used and the capacity 110 of the mill.

Tubes made as above described are

stronger, gage for gage, than drawn seamless tubes now made. The tubes thus formed are finished by any of the ordinary methods.

If, for any reason, the mandrel adheres to the tube then the tube can be given a flash heat so as to expand the tube without affecting the mandrel and then can be further treated to break the adhesion.

I claim:—

10. 1. The process of making a seamless tube, said process consisting in taking a hollow ingot, forcing the ingot over a mandrel of a uniform diameter throughout and reducing the ingot to form a tube, then acting on the metal of the tube in a longitudinal line so as to slightly enlarge the tube, and then car-

rying the enlargement around the tube and finally withdrawing the mandrel from the tube.

2. The process of making a seamless tube, 20 said process consisting in first taking a hollow ingot, forcing the metal of the ingot over a mandrel of a uniform diameter throughout and reducing the ingot to form a tube on said mandrel, then hammering the 25 tube on a longitudinal line so as to form a slight buckle or enlargement on the tube, then rolling the tube laterally to carry the buckle around the mandrel, freeing the tube therefrom, and finally withdrawing the man- 30 drel from the finished tube.

WALLACE E. HUGHES.
